UNITED STATES PATENT OFFICE.

JACOB SOKOLOV, OF NEW YORK, N. Y.

DOOR-LOCK.

1,227,684.

Specification of Letters Patent.

Patented May 29, 1917.

Application filed April 28, 1916. Serial No. 94,133.

To all whom it may concern:

Be it known that I, JACOB SOKOLOV, a citizen of the United States, and a resident of the borough of the Bronx, county of Bronx, city and State of New York, have invented certain new and useful Improvements in Door-Locks, of which the following is a specification.

My invention relates more particularly to door locks of the dead bolt type—that is, locks in which the bolt when in locked position cannot be retracted without the use of a key or other suitable tumbler mechanism. In locks of this type it is usual to have a detent of some kind which is adapted to drop into position when the bolt is in locked position and hold the bolt from being pushed back by direct pressure upon the end of the bolt. The detents ordinarily used for this purpose depend upon a spring to hold them in place and one of the objects of my improvement is to provide a detent for the lock which shall be positively operated by the key or other tumbler mechanism into position to prevent the bolt from being retracted or thrust back by direct pressure against the bolt itself.

In locks of this type it may occur that, although the bolt cannot be thrust back because of the detent, the door casing or keeper may be thrust to one side so that the door can be released and opened by unauthorized persons. It has frequently occurred that a jimmy or other burglar's implement has been employed to spring the door or door casing so as to release the lock bolt from the keeper without forcing the bolt back into the lock. In order to meet this objection to the ordinary dead bolt lock, I have provided the head of the bolt with a member adapted to be thrust out transversely to the bolt so as to provide lugs adapted to stand back of the keeper and engage the faces thereof if any attempt is made to forcibly withdraw the bolt through the keeper, either by the use of a jimmy or otherwise.

It is desirable that this safety device should be positively operated by the key or tumbler mechanism and both it and the detent which holds the bolt in locked position preferably should be positively locked so that any one attempting to tamper with the lock could not move or disengage these

parts. To accomplish this purpose, I preferably provide means whereby the keeper locking member in the end of the bolt is positively operated and locked in position by means of the key or tumbler mechanism which is adapted to operate the bolt.

One embodiment of my improvement is shown in the accompanying drawings, in which—

Fig. 1 is a cross-section removing the top of the cover of the lock so as to expose the bolt and the parts associated therewith (line A—A of Fig. 2).

Fig. 2 represents a vertical transverse section on the broken line 2—2 of Fig. 1.

Fig. 3 is a view similar to that shown in Fig. 1 with the bolt in retracted position.

Fig. 4 is a side elevation of the lock attached to a door, looking toward the end of the bolt which is in locking position.

Fig. 5 is an end view with the bolt shown in section along the line 5—5 of Fig. 1 before the cross bolt is turned.

Fig. 6 is a vertical transverse section through the case and bolt on the line 6—6 of Fig. 1; and

Fig. 7 represents a longitudinal section of the lock attached to the door together with a portion of the door casing and the keeper, the bolt being in locked position.

Referring to the drawings 1 represents the hollow box-like casing in which the parts of the lock are assembled. The bottom of the casing is preferably closed by a plate 2 which may be secured in place by screws in the usual or any preferred manner. One end of the casing at 3 is slotted or provided with a rectangular opening through which the bolt 4 may be projected when in locked position. The bolt 4 may be guided in any preferred manner but preferably I provide a lug 5 extending from the wall of the casing 1 and adapted to fit in a slot 6 in the narrow inner end 7 of the bolt 4, substantially as indicated in Figs. 1 and 3 of the drawings. The head of the bolt is preferably wider and thicker than the rear portion thereof which is cut away so that it is preferably about half the width of the bolt head, as indicated in the drawings. This narrow rear portion 7 of the bolt is preferably provided at 8 with a notch adapted to cooperate with a pin 9 extending laterally from a crank arm 10 secured to a shaft or stud 11,

as indicated in Figs. 1, 2 and 3 of the drawings. This crank arm 10 preferably extends beyond the edge of the narrow portion 7 of the bolt and assists in positioning the bolt 4 while the pin 9 is adapted by coöperation with the notch 8 to operate the bolt 4 and move it either into or out of locking position in the usual manner. The crank arm 10 and pin 9 are, in the present instance, shown as secured to a finger wheel or knurled knob 12 connected with the shaft or stud 11, as indicated in Figs. 2 and 7 of the drawings. The knob 12 and connected parts may be held in the normal position by a detent in the usual or any preferred manner. Preferably, I make the shaft 11 long enough to extend nearly to the bottom plate of the lock and provide it with another similar but loosely fitting crank arm 13 provided with a pin 14 corresponding with the pin 9 and extending in the opposite direction but in axial alignment therewith, as indicated in Fig. 2 of the drawings. The crank arm 13 is preferably provided with a hub 15 which, in the usual manner, is slotted at 16 to be engaged by a tongue strip 17 connected with the key tumbler barrel 18 adapted to be operated by a key 19 in the usual or any preferred manner. Both of the pins 9 and 14 operate in this notch 8 to throw the bolt in either direction, however, as the two crank arms 10 and 13, are independently mounted, either one can be operated without operating or turning the other. This is desirable in order that the bolt may be thrown by turning the knob 12, which would be on the inside of a room, or by means of a key in the tumbler barrel 18, located on the outside of the door in the usual method of attaching locks of this type.

As previously indicated, it is desirable in locks of this character to positively lock the bolt 4 when in locking position so that it cannot be forcibly pushed back into the lock by pressure upon the bolt. For this purpose I preferably provide the bolt 4 with a vertical, transverse hole or slot at 20 and mount therein a detent member 21 adapted to coöperate with a suitable fixed stop 22, connected with or secured to the casing 1 of the lock. In the present instance, I have preferably shown an integral partition 23 extending inward from the lower edge of the bolt opening 3 of the end of the casing 1 and provided with a hole 22 into which the lower end of the detent member 21 is adapted to enter when the bolt 4 is in locking position, as indicated in Fig. 1 of the drawings.

It is desirable that this detent 21 shall be positively moved into position to lock the bolt 4 and require to be positively withdrawn from the hole 22 to unlock the bolt 4 when it is desired to retract the latter. This positive movement of the detent 21 I pref-

erably accomplish by providing the upper narrow portion of the bolt 7 with a longitudinal slidable U-shaped plate or cam member 24 provided on one side with an arm 25 in which a cam slot 26 is formed. The upper end of the detent member 21, in the present instance, is provided with a pin 27 extending laterally therefrom through a slot 27^a in the side wall of the bolt 4 and into the cam slot 26, as indicated in Figs. 1, 3 and 6 of the drawings. This cam plate 24 is preferably held in place by suitable lugs 28, 28^a and 29 projecting from the casing 1 and plate 2, as indicated in Figs. 1, 2 and 3 of the drawings, and adapted to lie along the sides 80 and back or upper side of the narrow portion 7 of the bolt 4.

The cam plate 24 is preferably adapted to be slid or moved longitudinally and independently of the bolt by means of the tumbler devices which are adapted to operate the bolt 4 previously described. In order that this may be satisfactorily accomplished, the plate 24 is provided at 30 with notches having segmental faces adapted to 90 coöperate with arms 31 and 32, forming part of and extending radially from the crank arms 10 and 13, as indicated in Figs. 1, 2, 3 and 7 of the drawings. Additional notches 33, of any suitable shape, are provided on each side of the cam plate 24 to permit the passage of the arms 10 and 13 and the pins 9 and 14 when one or the other of the latter is passing through the slot or notch 8 while operating the bolt, as indicated in Fig. 3 of the drawings. It will be seen, therefore, that the notches 30 and the coöoperating arms or lugs 31 and 32, correspond to a single tooth gear and rack construction for transforming the circular movement of the tumbler devices into longitudinal movement of the cam plate 24, independently of the movement of the bolt 4—7. The movement of the cam plate 24 is independent of the movement of the bolt 4—7 in order that the cam 26 operating on the pin 27 may operate the detent 21 either after the bolt is thrown by the tumbler devices or just before it is thrown. This operation of the detent member is 115 timed to occur only when the bolt 4 is in locking position—that is, when it is in the position shown in Figs. 1 and 7 of the drawings.

I have previously pointed out that I provide means for preventing the keeper from being forcibly removed from the bolt 4 or in other words to prevent unauthorized persons by means of a jimmy or otherwise from forcibly opening the door to 125 which the lock is attached. For this purpose I preferably provide the head or end of the bolt 4 at 34 with a transverse slot or opening in which there is mounted a winged disk or cross bolt member 35 which 130

is preferably pivoted on a shaft 36 extending longitudinally of the bolt head and having bearings therein, the arrangement being substantially as shown in Figs. 1, 3 5 and 5 of the drawings. The inner end of the shaft 36 is preferably provided at 37 with pinion teeth adapted to mesh with rack teeth 38 cut on the inside of the detent member 21, as shown in Fig. 6 of the drawings. The cross bolt member 35 is 10 preferably secured to the shaft 36 by means of a pin or screw 39 after the shaft is placed in position, although, obviously, any other suitable method of securing the parts 15 together in operative relation may be employed. The cross bolt member 35 is provided with flattened sides 40 on each side of the shaft 36 in parallel relation so that when the disk or member 35 is in unlocked 20 position, the member will preferably lie within the planes of the sides of the bolt 4 and will, therefore, pass readily through the keeper opening 41 of the keeper 42 as the bolt is thrown into or withdrawn from 25 locking position. The cross bolt locking member 35 is shown in normal inoperative position in Figs. 3 and 5, the view in Fig. 5 representing the bolt as thrown to locking position but before the tumbler devices have 30 operated the slide plate 24 to set the detent 21 and turn the member 35 crosswise of the bolt, the latter position being indicated in Figs. 4 and 7 of the drawings. It will be seen that by connecting the cross bolt locking member 35 with 35 the detent member 21 the member 35 is positively operated by means of the tumbler mechanism at the same time that the detent member 21 is operated. The slide 40 member 24, therefore, is adapted to positively throw the cross bolt 35 into locking position back of the walls of the keeper, as indicated in Fig. 7 of the drawings after the bolt 4 is thrown into locking position. 45 The cam slot 26 is preferably provided with a flat portion at 26^a, near the inner end of the arm 25, which engages the pin 27 when the slide plate 24 is in forward position and the detent 21 in locking position to 50 positively prevent the detent from being lifted by turning or exerting pressure upon the cross bolt member 35 thus rendering it impossible for any one to remove the cross bolt ends from locking position back of the keeper 42 or to lift the detent in order that the bolt 4 might be forcibly restored to normal position inside the lock casing. By 55 this provision it will be seen that only by means of the knob 12 or the key tumbler mechanism 18 operating through the tumbler cams 31 or 32 and pins 9 or 14 can the bolt 4 be unlocked, the cross bolt 35 being turned in order that it may pass through the keeper and the detent lifted. 60 65 The operation of the device will be un-

derstood from the description given in connection with the drawings and may briefly be described as follows:

If the lock is attached to a door and the parts are in the position indicated in Figs. 1 and 7 of the drawings, the door is locked and the cross bolt member and detent are in locking position to coöperate respectively with the keeper and the notch or hole 22 in the member 23. The tumbler mechanism 70 will be in such position that the pins 9 and 14 and cam arms 31 and 32 are substantially in the position indicated in Fig. 1 of the drawings. If now the shaft 11 is turned by means of the knob 12, the cam arm 31 will 75 first come in contact with the side walls of the slot 30 in the cam plate 24 and move the latter toward the left relatively to the bolt 4—7 to the position it occupies in Fig. 3 of the drawings. This movement of the cam plate 24 causes the cam 26 by coöperation with the pin 27 to lift the detent 21 out of the hole 22 and by means of the rack and pinion connection 37—38 the cross bolt 35 will be turned from the position indicated 80 in Figs. 1, 4 and 7 to the position indicated in Figs. 3 and 5, the detent 21 being adapted to clear the plate 23. Further movement of the shaft 11 brings the pin 9 into engagement with the notch 8 in the narrow portion 7 of the bolt 4 and the bolt together with the parts carried thereby is moved or 85 drawn inward to the position shown in Fig. 90 3 of the drawings.

When it is desired to lock the door by 100 throwing the bolt to locking position, the reverse operation takes place—that is, the parts to start with are in the position indicated in Fig. 3 of the drawings and the shaft 11 is turned in the opposite direction—or, as viewed in Fig. 3, clockwise, so as to bring the pin 9 into engagement with the notch 8 and throw the bolt toward the right or into locking position and then the cam arm 31 is brought into position to engage the notch 30 of the cam plate and move it toward the right relative to the bolt 4 into the position shown in Fig. 1 of the drawings, thereby positively actuating the detent 21 and the cross bolt member 35. 105 They will then be in position to positively prevent the forcible retraction of the bolt or the forcible removal of the keeper 42 off the end of the bolt. The parts will be positively locked in this position by the flat portion 26^a of the cam lever so that they can be 110 restored to normal position only by the action of the tumbler devices, either through the knob 12 or the key 19 acting through the connecting member 17 and the crank arm 115 13, as described.

It will be understood that I have herein shown and described one form of my device but obviously various modifications and adaptations of the mechanical elements em- 120 125 130

ployed may be made and various modifications in the specific details of construction might be devised by those skilled in the art without departing from the spirit and scope 5 of my invention, and, therefore, I do not wish to be limited to the particular construction shown.

I claim:

1. A door lock comprising a slide bolt 10 adapted to coöperate with a keeper, a member adapted to be projected laterally from the bolt head to prevent withdrawal thereof through the keeper, a detent adapted to hold said bolt in thrown position, said detent and 15 said member being connected to operate in unison, means for locking said detent and member against forcing and tumbler devices for positively operating the bolt, said detent and said locking means in sequence.
2. A door lock comprising a slide bolt, a cross bolt mounted in the end of the slide bolt and adapted to be projected laterally therefrom, a movable detent for holding said slide bolt in locked position, and means 20 connecting said cross bolt and the detent to operate in unison whereby when the detent is in position to hold the slide bolt against retraction, the cross bolt is projected therefrom.
3. A door lock comprising a slide bolt, a cross bolt mounted in the end of the slide bolt and adapted to be projected laterally therefrom, a movable detent for holding said slide bolt in locked position, means connecting said cross bolt and the detent to 25 operate in unison whereby when the detent is in position to hold the slide bolt against retraction, the cross bolt is projected therefrom, and tumbler devices adapted in unlocking said lock to first lift said detent and withdraw said cross bolt and then withdraw said slide bolt.
4. In a door lock of the character described, the combination with a keeper of a 45 bolt adapted to enter said keeper when in locked position, a member pivoted on said bolt and provided with portions adapted to be turned out of the bolt, back of said keeper when said bolt is in locked position, means for locking said member against forcing and tumbler devices for moving said bolt, adapted, when the bolt is in locked position, to positively turn said pivoted

member and lock it, whereby the latter becomes operative to prevent forcing the bolt 55 out of the keeper.

5. In a door lock of the character described, the combination with a keeper of a bolt adapted to enter said keeper when in locked position, locking members adapted 60 to be thrust out back of said keeper, transversely of the bolt, to lock the latter against forcible withdrawal from said keeper, a detent for locking said bolt in locked position in the keeper, and tumbler means adapted 65 to simultaneously operate said detent and said locking members when said bolt is in locked position.

6. In a door-lock of the character described, the combination with a slidable bolt 70 adapted to enter a keeper, the head of said bolt being provided with a slot, a locking member pivotally mounted in said slot and adapted to be turned out of the bolt into a position to prevent forcing the bolt out of 75 the keeper, a detent for locking the bolt in locked position, a cam-plate adapted to operate said detent and said locking member simultaneously, and tumbler devices for throwing said bolt, adapted, when the bolt 80 is in locked position, to operate said cam-plate whereby said detent and locking member are operated after locking and before unlocking said bolt.

7. In a door-lock of the character described, the combination with a slidable bolt adapted to enter a keeper, the head of said bolt being provided with a slot, a segmental disk pivotally mounted in said slot, the diameter of the disk being greater than 85 the thickness of said bolt but having opposite sides cut away to leave a width the thickness of the bolt, a detent adapted to lock said bolt in locked position, said detent and segmental disk being connected together to operate in unison so that when the detent is in locking position said segmental disk is turned crosswise of said bolt head, a slide plate adapted to operate said detent and disk, means for locking said detent and disk against movement, and tumbler devices for sliding said bolt, adapted to operate 90 said slide plate and said last named means for locking said detent and disk substantially as described.

JACOB SOKOLOV.
